SUCTION NOZZLE WITH BRUSH AND WIPER

Bettie A. Udell, La Junta, Colo.

Application August 19, 1949, Serial No. 111,178

1 Claim. (Cl. 15—367)

1

This invention relates to brushes.

An object of this invention is to provide a brush which is designed for cleaning the interior of footwear, and also for cleaning and polishing the exterior thereof.

Another object of this invention is to provide a brush which is formed of a hollow body ovoidal in plan and having openings so that a suction means may be coupled thereto for removing dirt or the like from the interior of the footwear.

A further object of this invention is to provide a brush which has sheep's wool secured about a hollow body, with bristles projecting from the wool in a horizontal plane so that dirt or loose particles may be readily loosened and removed from the interior or exterior of footwear.

With the above and other objects in view, my invention consists in the arrangement, combination and details of construction disclosed in the drawing and specification, and then more particularly pointed out in the appended claim.

In the drawing,

Figure 1 is a plan view, partly in section, taken on the line 1—1 of Figure 2 of a brush constructed according to an embodiment of this invention.

Figure 2 is a sectional view taken on the line 2—2 of Figure 1.

Figure 3 is a sectional view taken on the line 3—3 of Figure 1.

Referring to the drawing, the numeral 10 designates generally a hollow body which is formed of a bottom wall 11 having openings 13 therethrough, and a transversely arcuate top wall 12. The configuration of the body or housing 10 is substantially ovoidal in plan, as shown in Figure 1.

A wool covering 14 is secured over the housing 10 and includes the leather 15, with the wool 16 secured thereto. The leather 15 where it extends over the bottom wall 11 is formed with openings 17 registering with the openings 13 so that when the housing or body 10 is connected with a vacuum cleaner, dirt or loose particles may be drawn through the openings 13 and 17.

The body or housing 10 includes a nipple 18 at the rear thereof, with which a tubular handle or connecting member 19 is secured. The device may be used by grasping the tubular handle 19 and extending the same into the interior of a

2

shoe, or if desired the tubular member 19 may be connected with a vacuum cleaner.

A plurality of laterally extending bristles 20 are carried by the covering 14 and terminate at 5 a point, as shown in Figure 1, forwardly of the rear of the brush structure. The bristles 20 are provided so that dirt in the corners of overshoes or shoes may be loosened.

With a brush structure as hereinbefore described, the brush is extended into the interior of a shoe or overshoe so that the entire interior of the shoe or overshoe may be thoroughly cleaned. If desired the brush structure may be connected by tubular handle 19 to the suction 15 end of a vacuum cleaner in order to draw out the loose particles within the shoe or overshoe.

I do not mean to confine myself to the exact details of construction herein disclosed, but claim all variations falling within the purview of the 20 appended claim.

What I claim is:

A brush structure for cleaning the interior of a shoe or the like comprised of a hollow ovoidal body of rigid material having an apertured flat 25 bottom wall corresponding in shape to the interior of a shoe, a tubular handle and connector for suction extending obliquely from the rear of said body and communicating with the interior thereof, a leather covering for said body having 30 apertures therein aligned with the apertures in said bottom wall, a sheep's wool outer covering secured to said leather covering, and a plurality of bristles extending through said sheep's wool covering and secured to said leather covering, 35 said bristles forming a radial row extending about the front of said body.

BETTIE A. UDELL.
